sum Company, Chicago, Ill., a corporation of
Illinois

Application July 20, 1933, Serial No. 681,307

22 Claims. (Cl. 20—4)

This invention relates to improvements in acoustical construction and has particular relation to acoustical coverings for walls, ceilings, and the like, all of which are intended to be comprehended within the generic term "walls".

The use of various types of rigid sound-absorbing materials of a porous nature, or the like, as acoustical wall coverings, has been known in the art for many years. Such materials have included porous plasters, fibrous tile products, ceramic tile, aggregations of slag, cork, and the like, mineral wool slabs, etc. Many of these products cannot be painted without destroying their acoustical qualities, because the paint fills the pores at the surface and prevents entrance of the sound waves which impinge thereon. Paintability has been achieved to some extent with some tile products by making the same with very rough open surfaces, but such surfaces present a very poor and non-uniform appearance and are lacking in the desired qualities of smoothness and light reflection.

The present invention is directed to arrangements for overcoming the above-mentioned difficulties and objections.

The primary object of the invention is to provide a construction in which a rigid sound-absorbing material of relatively poor or unsatisfactory appearance may be used as the primary absorbing medium, while the finished product of construction may be made to have a good appearance and desirable qualities of cleanability, paintability, high light deflectivity and comparative freedom from collection of dust and dirt.

A further object of the invention is to provide a product or construction, the surface of which may be readily modified to satisfy the desires of individuals or the requirements of particular installations.

In a copending application filed Oct. 4, 1933, Serial No. 692,078 in the names of the inventors in the present case, there is disclosed and claimed an invention comprising an acoustical construction made up of a compressible sound-absorbing material, faced with a flexible membrane which is substantially impervious to the passage of air.

The present invention likewise employs a substantially impervious membrane, but includes a rigid sound-absorbing material rather than a compressible material. This invention is based upon the discovery that sound-absorbent products which are not easily compressible or flexible may be surfaced with a flexible but substantially impervious membrane, providing the membrane is placed loosely on the surface of the ab-

sorbent material and not glued or otherwise secured thereto over the entire surface thereof. Various adaptations of the invention embodying this principle are described in detail hereinafter, by way of example of the numerous modifications which may be employed.

The invention will be better understood upon reference to the detailed description appearing hereinafter, in conjunction with the accompanying drawings forming a part hereof, in which:

Figure 1 is a fragmentary sectional view of a wall which has been acoustically treated in accordance with the invention;

Fig. 2 is a fragmentary front elevational view of the construction shown in Fig. 1, indicating by the line 1—1, the plane on which the sectional view of Fig. 1 is taken;

Fig. 3 is an enlarged fragmentary sectional view of one of the wall-covering elements shown in Figs. 1 and 2, taken on a plane such as that indicated by the line 3—3 in Fig. 2;

Fig. 4 is a view similar to Fig. 3 but showing a modified type of construction of one of the wall-covering elements;

Fig. 5 is an enlarged fragmentary front elevational view of the element shown in Fig. 3, with certain of the parts broken away to illustrate the construction more clearly;

Fig. 6 is a view similar to Fig. 5, but illustrating the modified type of construction of Fig. 4;

Fig. 7 is a fragmentary sectional view of a wall, similar to Fig. 1 but showing a different type of construction;

Fig. 8 is a fragmentary front elevational view of the construction of Fig. 7, indicating by the line 7—7 the plane on which the sectional view of Fig. 7 is taken;

Fig. 9 is an enlarged fragmentary sectional view taken on the same plane as Fig. 7, but illustrating the construction in greater detail by reason of its enlargement; and

Fig. 10 is an enlarged fragmentary front elevational view of the construction shown in Fig. 9, with parts broken away to give a more detailed illustration.

Referring first to Figs. 1 to 6 of the drawings, a wall of any ordinary type is illustrated by way of example as being formed of hollow tile or slabs 11 of gypsum or the like. Over this surface the usual coat or coats of plaster 12 are applied in the usual manner, and this plastered surface is covered, for the purposes of acoustical correction, by a plurality of slabs or tiles 13, which are formed in accordance with the invention. These tiles may be secured to the plastered surface by

- a layer of cement or adhesive 14, as shown, or by any desired type of mechanical or other securing means. For the purposes of decorative appearance, the tiles may be suitably formed with beveled edges, as illustrated, and they may be made of any desired dimensions. A suitable tile may be made approximately 12" square and 1" thick, to give a good appearance and to be easily handled.
- 10 The tiles or slabs 13 may be made of any desired type of rigid sound-absorbent material, which materials are well known in the art, and a number of which have already been listed herein by way of example. The drawings are intended to illustrate fiber boards or slabs of any well-known type, but it will be readily understood that cementitious or ceramic materials, bonded aggregations or any other compositions may be utilized in the same manner.
- 15 20 All of the materials above mentioned, while highly effective as sound absorbents, present a poor appearance and have a comparatively rough and uneven surface of poor light reflectivity. They are also poorly adapted for painting and cleaning by reason of the fact that paint will fill the pores at the surface and destroy the acoustical properties, while cleaning will impair the surface appearance or result in uneven removal of a considerable quantity of fibrous or 25 similar material, as well as being comparatively ineffective in any event.
- 30 According to the present invention, the tiles or slabs 13 are faced with membranes 15 which are substantially impervious to the passage of air. In this respect such membranes are different from those of the prior art which have been made of a porous or perforated material. The pores or perforations in such prior art membranes have detracted in a large measure from 35 the desired qualities of appearance and protection to the sound-absorbing material behind the same. With the substantially impervious membranes to which reference is made herein, these objections are entirely overcome, and the finished 40 product or construction presents a surface of pleasing appearance and one which may be readily cleaned and painted and which may be made to have any desired degree of light reflectivity.
- 45 50 The membranes 15 may be made of numerous substantially impervious materials, the only other essential characteristic being flexibility, so that the membranes may vibrate freely under the impact of sound waves. Suitable materials 55 for the construction of the membranes are various grades and types of paper, metal foil, oil cloth, treated fabrics, wall paper, "cellophane", sheet mica, or any other material having similar qualities.
- 55 60 The only requirement as to the securing of the membranes is placed over the surfaces of the sound-absorbent material is that the membranes shall be free to vibrate independently of the absorbing material over a major portion of the exposed area. A suitable method of attachment of the membranes is illustrated in the drawings, which are intended to depict the use of glue or other adhesive along comparatively narrow strips or bands 16 around the edges of each of the slabs 65 or tiles. For this purpose a flexible glue gives desirable results, because the membranes may be secured in place under sufficient tension to prevent sagging, but not great enough to warp the slabs or tiles or to impair their acoustical efficiency. It will be understood, however, that 70 75

the membranes may be attached by nailing or other means, mechanical or otherwise, so long as the above noted requirements are complied with.

Figs. 3 and 5 illustrate the use of a membrane 5 15 of uniform thickness and appearance which may be constituted by ordinary or treated paper of any kind, or any of the other materials hereinabove enumerated. In Figs. 4 and 6 a modified type of membrane 15a is illustrated and consists 10 of crinkled or embossed paper or metal foil, or the like. A further slight modification embodied in this form of construction resides in the fact that the membrane is extended down over the beveled edges of the tiles or slabs, whereas in the 15 construction illustrated in Figs. 3 and 5, the membranes terminate along the lines where the beveled edges begin. Either arrangement may, of course, be used as desired.

When the membranes are made of paper, it is 20 preferable to have the same conditioned to a suitable water content, giving some degree of expansion before application, so that the desired tension will be maintained under varying conditions of humidity. The use of crepe or embossed 25 paper is advantageous in avoiding sagging under high humidity conditions, as well as avoiding excessive tension at any time.

It will be seen that the slab or tile unit type of construction is readily adapted for application to 30 a completed wall. The invention is not limited to this type of application, however, but may be applied with equal effectiveness in the original construction of a building or the like. Figs. 7 to 35 10 of the drawings illustrate the application of a coat of acoustic plaster to a wall surface. In these figures a different type of construction is illustrated as a further example, consisting of wood studs 17 to which are nailed plaster boards 18 forming a plaster-receiving base or lathing. 40

As shown in Fig. 9, such plaster boards may consist of a gypsum core 18a and paper covering sheets 18b, according to well-known construction. These boards are secured to the studs 17 by nails 19 in the usual manner and a coating of 45 ordinary plaster 20 may be applied over the surface of the boards to provide a base coat upon which a layer of acoustical plaster 21 is subsequently applied. Acoustical plasters of various 50 compositions are well known in the art and do not require detailed discussion herein. It will suffice to say that such plasters ordinarily consist of a porous material, whereby absorption of sound is obtained.

The present invention is embodied in this type 55 of construction by the use of a membrane covering 22 which may be applied in sheets of any desired size. Such membranes are secured in place over the surfaces of the acoustical plaster in much the same way that the individual membranes are applied in the above-described slab or tile construction, that is, by narrow strips or bands of adhesive 23 or other suitable securing means. The application of the adhesive in comparatively widely-spaced bands or spots 60 accomplishes the purposes of the invention by leaving the major portion of the membrane free to vibrate with respect to the sound-absorbent material directly behind it.

With any of the above-described types of construction the exposed surfaces of the membranes may be painted as desired without greatly affecting the acoustical efficiency of the complete construction. It will be understood, of course, that in an installation where one or more coats of 70 75

paint are to be applied to the membranes, the latter should be initially selected with a view to having sufficient flexibility so that the increase in stiffness due to painting will not make the 5 membranes too stiff to vibrate under the impact of sound waves. This quality can be readily determined for any desired type of installation and is not of a critical nature. The membranes may also be selected from a wide range of equivalents 10 to give any desired characteristics of cleanability, light reflection, etc.

From the foregoing, it will be seen that the invention resides in the provision of a substantially impervious membrane extending over the 15 surface of a rigid sound-absorbing material and secured in place in such a manner that the major portion thereof will vibrate independently of the sound-absorbing material. The elimination of 20 pores and perforations in the membrane provides a great improvement in the appearance and other desired characteristics of the installation over those which have been used heretofore. Moreover, the discovery of the fact that the 25 membranes may be secured in place over the surfaces of the rigid sound-absorbing material without being spaced outwardly therefrom, provides an economical and desirable type of construction which has been unknown heretofore.

In referring to the membranes as being substantially impervious to the passage of air, it 30 will be understood that a limitation to completely impervious and non-porous products is not intended. For example, paper and similar products might not be considered to be absolutely airtight, but, to all intents and purposes, they are 35 substantially impervious to the passage of air, and, therefore, fully comply with the requirements of the present invention.

Reference to the membranes as being in contact with the sound-absorbent covering over substantially the entire surface thereof, is not intended to mean that the membrane is always in 40 actual contact with the covering at every point on the surface thereof, but only that no intervening space is intentionally provided. Minute 45 spacing, resulting from slight sagging on the part of the membrane or irregularities in the surface of the sound-absorbent material, are not regarded as placing the membrane out of substantial 50 contact with the sound-absorbent material.

Other terms used in the foregoing description and appended claims will be readily understood from the context. The term "wall," as above indicated, is used generically to designate both 55 walls and ceilings, as well as any other partition or surface bounding a room or other enclosure. Reference to the "face" of such a wall or of a covering therefor designates the surface thereof which faces inwardly toward the room, as distinguished from the rear surface. The term 60 "covering" does not necessarily imply the extension of the covering layer over the entire surface of a wall, but may refer to only a portion of such wall surface.

While only certain specific embodiments of the invention have been shown and described in detail herein, it will be readily understood by those skilled in the art that various changes and modifications in the details of construction and arrangement of parts may be made without departing from the spirit and scope of the invention, as set forth in the appended claims.

What is claimed as new and is desired to secure by Letters Patent, therefore, is:

1. An acoustical construction comprising a wall having a normally exposed surface, a covering for said surface of rigid, sound-absorbent material, and a flexible membrane substantially impervious to the passage of air extending over the 5 face of said covering and in contact therewith over substantially the entire surface thereof, but free to vibrate with respect thereto over the principal portion of such surface.

2. An acoustical construction comprising a 10 wall having a normally exposed surface, a covering for said surface of rigid, sound-absorbent material, and a flexible membrane substantially impervious to the passage of air extending over the 15 face of said covering and adhesively secured thereto at spaced intervals.

3. An acoustical construction comprising a wall having a normally exposed surface, a covering for said surface of rigid, sound-absorbent material, and a flexible membrane substantially 20 impervious to the passage of air extending over the face of said covering and in contact therewith over substantially the entire surface thereof and adhesively secured thereto at spaced intervals. 25

4. An acoustical construction comprising a wall having a normally exposed surface, a covering for said surface of rigid, sound-absorbent material, and a flexible membrane substantially 30 impervious to the passage of air extending over the face of said covering and in contact therewith over substantially the entire surface thereof but free to vibrate with respect thereto over the principal portion of such surface, said membrane being of a cleanable material. 35

5. An acoustical construction comprising a wall having a normally exposed surface, a covering for said surface of rigid, sound-absorbent material, and a flexible membrane substantially impervious to the passage of air extending over the 40 face of said covering and in contact therewith over substantially the entire surface thereof but free to vibrate with respect thereto over the principal portion of such surface, said membrane being of a paintable material. 45

6. An acoustical construction comprising a wall having a normally exposed surface, a covering for said surface of rigid, sound-absorbent material, and a flexible membrane extending over the face of said covering and in contact therewith over 50 substantially the entire surface thereof but free to vibrate with respect thereto over the principal portion of such surface, said membrane being painted to render the same substantially impervious to air and water vapor. 55

7. An acoustical construction comprising a wall having a normally exposed surface, a covering for said surface of rigid, sound-absorbent material, and a flexible membrane substantially impervious to the passage of air extending over the 60 face of said covering and in contact therewith over substantially the entire surface thereof but free to vibrate with respect thereto over the principal portion of such surface, said membrane being of a material of relatively high light reflecting. 65

8. An acoustical construction comprising a wall having a normally exposed surface, a covering for said surface of rigid, sound-absorbent material, and a flexible membrane substantially impervious to the passage of air extending over the 70 face of said covering and in contact therewith over substantially the entire surface thereof but free to vibrate with respect thereto over the principal portion of such surface, said membrane 75

being of a material having a smooth and uniform surface.

9. An acoustical construction comprising a wall having a normally exposed surface, a covering for said surface of rigid, sound-absorbent material, and a flexible membrane substantially impervious to the passage of air extending over the face of said covering and adhesively secured thereto at spaced intervals by a flexible glue.

10. An acoustical construction comprising a wall having a normally exposed surface, a covering for said surface of rigid, sound-absorbent material, and a flexible membrane of water-conditioned paper substantially impervious to the passage of air extending over the face of said covering and adhesively secured thereto at spaced intervals.

11. An acoustical construction comprising a wall having a normally exposed surface, a covering for said surface of rigid, sound-absorbent material, and a flexible membrane of crepe-like paper substantially impervious to the passage of air extending over the face of said covering and adhesively secured thereto at spaced intervals.

12. An acoustical construction comprising a wall having a normally exposed surface, a covering for said surface of rigid, sound-absorbent material formed in tile-like units, and a flexible membrane substantially impervious to the passage of air extending over the face of each of said units and in contact therewith over substantially the entire surface thereof.

13. An acoustical construction comprising a wall having a normally exposed surface, a covering for said surface of rigid, sound-absorbent material formed in tile-like units, and a flexible membrane substantially impervious to the passage of air extending over the face of each of said units and adhesively secured thereto at spaced intervals.

14. An acoustical construction comprising a wall having a normally exposed surface, a covering for said surface of rigid, sound-absorbent material formed in tile-like units, and a flexible membrane substantially impervious to the passage of air extending over the face of each of said units and adhesively secured thereto along relatively narrow bands at the edges thereof.

15. An acoustical construction comprising a wall having a normally exposed surface, a covering for said surface of rigid, sound-absorbent material formed in tile-like units, and a flexible membrane substantially impervious to the passage of air extending over the face of each of said units and adhesively secured thereto at spaced intervals by a flexible glue.

16. An acoustical construction comprising a

wall including an extensive surface layer of rigid, sound-absorbent material and a flexible membrane substantially impervious to the passage of air extending over the face of said surface layer and in contact therewith over substantially the entire surface thereof. 5

17. An acoustical construction comprising a wall including an extensive surface layer of rigid, sound-absorbent material and a flexible membrane substantially impervious to the passage of air extending over the face of said surface layer and in contact therewith over substantially the entire surface thereof and secured thereto at spaced intervals.

18. An acoustical construction comprising a wall including an extensive surface layer of rigid, sound-absorbent material and a flexible membrane substantially impervious to the passage of air extending over the face of said surface layer and in contact therewith over substantially the entire surface thereof and adhesively secured thereto at spaced intervals. 15

19. An acoustical construction comprising a wall including a continuous surface layer of acoustic plaster and a flexible membrane substantially impervious to the passage of air extending over the face of said surface layer and in contact therewith over substantially the entire surface thereof and secured thereto at spaced intervals. 25

20. An acoustical construction comprising a wall having a normally exposed surface, a covering for said surface of rigid, sound-absorbent material, and an impervious paper membrane extending over the face of said covering and in contact therewith over substantially the entire surface thereof, but free to vibrate with respect thereto over the principal portion of such surface. 35

21. An acoustical construction comprising a wall having a normally exposed surface, a covering for said surface of rigid, sound-absorbent material, and an impervious metal foil membrane extending over the face of said covering and in contact therewith over substantially the entire surface thereof, but free to vibrate with respect thereto over the principal portion of such surface. 40

22. An acoustical construction comprising a wall having a normally exposed surface, a covering for said surface of rigid, sound-absorbent material, and an impervious cellophane membrane extending over the face of said covering and in contact therewith over substantially the entire surface thereof, but free to vibrate with respect thereto over the principal portion of said surface. 45 50 55
